UNITED STATES PATENT OFFICE

2,195,916

EGG CARTON ASSEMBLING MACHINE

Arthur Edmund Brown and William Vaughan,
London, Ontario, Canada, assignors to Leon
Benoit, New York, N. Y.

Application December 10, 1938, Serial No. 245,024

32 Claims. (Cl. 93—37)

The machine of the present invention is designed in its entirety to sequentially perform the various operations required in folding and then punching a procession of carton blanks each constituting the body of the egg carton, and in thereafter introducing the cross walls or partitions and interlocking the same in position in preparation for the final discharge of the assembled carton in knockdown condition at the discharge end of the machine. The machine in certain of its constituents embodies the features of construction shown and described in Patent No. 1,970,550, issued August 21, 1934, to Benoit et al., and Patent No. 1,993,915, issued March 12, 1935, to Brown and Vaughan, so that in the description of the present invention appropriate reference will be made to these patents.

In the present machine the scored carton blanks are placed flatwise in column form in a suitable hopper from which they are fed singly to breaker mechanism which breaks the carton blanks along the intended fold lines, and thereafter presents them in close folded condition to punch mechanism which punches the required slots and notches for the reception of the cross walls or partitions. Thereafter the punched once-folded blanks are delivered to the mechanism provided for inserting the cross walls through the slots in the body blank in preparation for the final operation, which reversely bends the center fold of the carton blank inwardly and up into the slots or lower notches in the cross wall partitions and flattens out the carton thus infolded in knockdown form for final delivery.

Certain features of novelty in the present machine are found in the department of the machine which serves to break the scored carton blank along the score lines, but the present features of the invention are directed mainly to the department of the machine which reversely bends the base wall of the carton blank upwardly into the notches in the cross walls for finally conditioning the carton for delivery from the machine.

In respect to the means provided for punching and notching the carton blanks, the mechanism employed in the present machine closely resembles that set forth and described in the Benoit Patent No. 1,970,550; and in the means provided for inserting the cross walls into the body blanks, the present machine closely resembles the machine of the Benoit patent aforesaid and also the machine of the Brown and Vaughan Patent No. 1,993,915, so that in respect to these mechanisms which are thus incorporated into the pres-

ent machine it will not be necessary to describe the same in such complete detail as in the case of those portions of the machine which more particularly embody the features of novelty above referred to.

The machine as a whole is so designed that the carton body blanks may be stacked flatwise at the forward end of the machine, and the cross walls likewise stacked at an intermediate point of the machine, after which the operations involved in breaking, punching and assembling the blank constituents and in folding and delivering the same will proceed continuously and automatically so that the cartons in knockdown column form and in condition for final shipment will be delivered by a continuous process so long as the required stack of blanks is supplied to the machine.

Further objects and details will appear from a description of the invention in conjunction with the accompanying drawings, wherein—

Figure 1 is a diagrammatic elevation view of the entire machine;

Fig. 2 is a collective view showing the condition assumed by the carton blanks at various stages during their progress through the machine;

Fig. 23 is a cross sectional view of the blank 15 after the folding operation is complete;

Fig. 24 is a longitudinal section through the middle of the carton blank on line 24 of Fig. 23;

Fig. 25 is an end view of a carton of modified form erected in its ultimate condition for use;

Fig. 26 is a detail of the grooved presser bar 20 for acting upon the base of the carton blank;

Fig. 27 is a detail of the grooved folder bar 25 for acting upon the top of the carton blank; and

Fig. 28 is a plan view of the hopper for receiving the folded blanks for final delivery.

The machine as a whole comprises a hopper A for receiving the carton body blanks in unfolded condition; breaker mechanism B for once-folding the blanks and breaking the same along the 30 score lines; punch mechanism C for punching the slots and notches in the once-folded carton blanks; assembling mechanism D for inserting the cross walls through the once-folded body blanks; mechanism E for infolding the body 35 blanks up into the notches in the cross walls; and hopper mechanism F for receiving and delivering the folded blanks in knockdown condition.

By reference to Fig. 2, it will be noted that 40 the machine begins its operation on a scored laid out flat body blank, a column of which blanks are stacked in the hopper A. The breaker mechanism B acts to fold the body blank along the medial score line, and to break the blank 45 along certain of the remaining score lines, giving it the appearance in cross section of an arrow. As the blanks thus broken or weakened along the score lines are fed forward, they are flattened into the once-folded condition and punched in 50 the section C of the machine as indicated in the accompanying view of the blank in Fig. 2. Thereafter the cross walls are fed through the blanks, as indicated in the view of the carton immediately beneath the mechanism D. Thereafter 55 the carton proceeds in the form shown in the right hand portions of Fig. 2, and is ultimately delivered with the medial section infolded, as shown, and the cross walls flattened to nest upon one another, so that the cartons in knockdown condition may be stacked in column 60 form for delivery.

Referring particularly to Fig. 3, the body of the carton is formed from a blank 30 which is 65 medially folded along a score line 31 which divides the body of the carton into two sections. The carton body is folded downwardly to afford adjacent longitudinal partition sections 32 which extend medially of the complete carton and at the base are spread outwardly along the fold 70 lines 33-33 forming the base sections 34-34 which diverge outwardly and downwardly to the inverted ridges 35 which afford the lines of contact for supporting the carton. The carton body is thence folded upwardly on each side along the 75 ridge lines 35 to afford side walls 36-36 which

terminate at the hinge lines 37, beyond which the carton blank provides cover walls 38 each connected along a fold line 39 with the marginal tucking flap 40.

The arrangements shown provides two trough-like sections which are divided into compartments by cross walls 41 which, as shown, are seven in number. The cross walls are configured, as best shown in Fig. 23, being of generally rectangular formation with an upwardly extending 10 lower slot 42 and an inwardly extending upper slot 43 in vertical alignment with one another and separated by a bridge section 44. The lower inner edges 45 of the cross walls are beveled inwardly to the mouth of the lower slot 42, and at 15 the outer end of each beveled section is formed a notch 46. The upper edge of each cross wall is provided at each outer corner with an upwardly projecting stop finger 47, and the terminus of the upper slot 43 is beveled away or 20 throated as at 48.

The position occupied by the cross walls with respect to the distended body of the carton when finally erected for use is indicated in Fig. 3, and the condition of the carton body when infolded 25 but with the cross walls distended laterally is indicated in Fig. 23. The erected condition of the carton shown in Fig. 3 does not occur in the present machine but is referred to for purposes of clarity in understanding the nature of the 30 completed carton here involved.

During its progress through the machine, the carton body blank is punched to provide a row of outer slots 49 and a row of inner slots 50, which latter are connected with the medial folding line 31 by slits 51 which terminate in notches 52 in the folded area.

The body blanks 30 are stacked flatwise within in a hopper 53 comprising angled corner standards 54 which receive and guide the corners of 40 the blanks. The column of blanks is supported upon a sloping feeding plate 55 which is mounted upon a slide bar 56 operating within guideways 57. The feeding plate near its rear edge is provided with a shoulder 58 which is adapted 45 to engage the outermost edge of the lower body blank and feed the same forward through a slot 59 below the gate plate 60 and into the bite of the feed rolls 61. Reciprocating motion is imparted to the feeding plate through an eccentric rod 62 which rides upon a cam 63 mounted upon a cam shaft 64.

The feed rolls 61 serve to advance each blank singly along a narrow central supporting bar 65 upon which the blank is centrally disposed 55 as indicated in dotted lines in Fig. 8, with its side edges projecting laterally and its forward edge in contact with a stop 66 (Fig. 5). In order to positively position each blank after it has passed beyond the bite of the rollers a kicker 67 is provided which is pivoted at the upper end of a rocker arm 68 and operated by a cam arm 70 actuated by a cam 71. The centrally disposed supporting bar 65 engages the middle of each blank, but the outer edges are 65 supported each upon the face of a folder plate 72 when the folder plates stand in extended relation as shown in Fig. 8. The folder plates are carried by arms 73 and 74, each pivoted at 75 to the frame of the machine. The arm 73 70 terminates in a straight section 76 while the arm 74 terminates in a bend or angle section 77.

The arms are swung in opposition to one another through the medium of slotted bracket heads 78 and 79, which straddle a cam shaft 75

80 upon which are mounted cams 81 and 82 which engage rollers 83 carried by the respective bracket heads for imparting opposed oscillatory movements to the arms 73 and 74 through 5 the medium of connecting rods 84—84. As a result of this arrangement the folding arms are moved toward and away from one another in unison so that the edges of the carton body blanks which initially lie flatwise against the 10 folder plates 72 will be carried upwardly as the bars are swung inwardly.

The folder plates are of a size to substantially enclose the once-folded carton blanks, and are configured as in Fig. 8 to afford a lower offset 15 groove 85 which merges into the flat inner face of the plate, which flat face along its upper margin is offset to afford a flared lip 86. The configuration referred to is such that when the two plates are swung to their innermost positions, 20 as in Fig. 7, they will enclose an arrow shaped space and impart to the carton blank a series of folds or breaks along score lines which coincide with the angles afforded by the inner faces of the folding plates. The folding plates 25 in conjunction cooperate with an anvil bar 87 which comprises a wedge shaped lower head 88 and a flared upper tail piece 89, giving to the anvil as a whole an arrow shape in cross section which is complementary to the configuration of 30 the folder plates, so that when the side edges of the carton blank are folded upwardly by the folder plates they will break along the angles afforded by the anvil and assume the configuration shown in Fig. 7, with the upper marginal 35 edges of the blank flaring outwardly between the beveled walls of the tail piece 89 and the flared margins 86 of the folder plates.

The anvil as a whole is suspended by a plate 90 from the frame of the machine, with its 40 inverted apex held slightly elevated above the central supporting bar 65 which affords a slight clearance for the insertion of the carton blank while lying flatwise. The stop 66 is provided with a notch 91 in its center, so that the stop 45 is effective only for retarding the blank while lying flatwise, but when folded upon the anvil by the action of the folder plates the carton will clear the stop 66 and may be carried forward through the notch 91. This forward advance 50 of the broken and folded carton is effected in the first instance by a kicker finger 92 carried by an arcuate arm 93 pivoted to a rock shaft 94 journaled within a bracket 95.

The rock shaft is actuated by an arm 96 to 55 which is pivoted a thrust rod 97, which in turn is actuated by cam mechanism 98 properly timed to actuate the kicker finger 92 at a time when the folder plates 72 have begun to retract and release the folded carton from confinement. The 60 kicker finger operates within slots 99 in the folder plates, which arrangement affords clearance for the movements of the kicker finger which projects the forward edge of the folded carton forwardly into the bite of rollers 100 operating on a vertical axis, which rollers engage the middle portion of the folded carton blank and feed it forwardly.

As the carton is fed between the rollers, its 70 lower folded edge and the upper margins will project respectively below and above the rollers, so that the carton as a whole will be free to expand and assume a once-folded flatwise condition in preparation for its advance into the die cutting or punching department of the machine 75 illustrated at C in Fig. 1, and illustrated in detail

in Fig. 9. This punching mechanism is practically identical with that shown in the Benoit Patent No. 1,970,550, so that it is not necessary to describe the same in full detail. It will suffice to point out that the once-folded carton blanks 5 are fed forward into position to stand against the inner face of a vertically standing female die plate 101 provided with a row of upper die slots 102 and a row of lower die slots 103. The die slots cooperate with upper male die members 104 10 and lower male die members 105 which are carried by a plate 106 which is mounted to swing upon an axis 107 through the action of suitable cam mechanism 108 and connections 109, which need not be described in detail. 15

The advance of the male die members inwardly results in the cutting of the upper row of slots 49, the lower row of slots 50, the slits 51, and the notches 52, all as illustrated in Fig. 2, which operation prepares the carton blank for the reception and interlocking of the cross partitions, which occurs in the next department D of the machine now to be described. 20

The folded carton blanks, after being punched, are advanced forwardly through the action of 25 kicker mechanism 110 identical with that shown in the Benoit Patent No. 1,970,550, and which need not be described in detail. This kicker mechanism advances the folded and punched carton blanks into the bite of vertically standing power driven feed rollers 111—111 (Figs. 10 and 11), which advance the blanks into the bite of feed rollers 112—112, at which point the carton blanks occupy the position indicated in dotted lines in Fig. 13, with their folded lower edges 30 upon a shouldered guide bar 113, from which extend inwardly a pair of inclined transverse rails 114, each having its upper edge 115 beveled to afford a sharp ridge which affords an incline for elevating the carton blanks to the right hand 40 position shown in full lines in Fig. 13 as the blanks are shoved sideways, and ride along the rails 114 which engage the outermost notches 52 in the folded lower edge of the carton blank. 35

The companion upper free edges of the carton 45 blank are held within a guide bar 116 of inverted channel form (Fig. 13) which is supported by brackets 117 at the required height to allow for the passage of the once-folded carton blanks within the space subtended between the 50 shouldered lower bar 113 and the upper channeled guide bar 116.

An accurate positioning of the cartons is effected by the movements of a kicker finger 118 (Fig. 11) which is mounted upon a vertical rock 55 shaft 119 having at its lower end a crank 120 suitably actuated through connections 121 by a cam 122. The rock shaft is journaled within a bracket head 123, and the arrangement as a whole is such that at properly timed intervals 60 the kicker finger will be oscillated to move the carton blanks forward against a suitable stop which holds them accurately in position to bring the notches 52 in the lower folded edge of the carton blank into registry with the inclined rails 65 115 which serve thereafter to transport the carton blanks into the required position to receive the cross walls.

With the cartons so positioned, but still occupying the outermost position indicated in dotted 70 lines in Fig. 13, the cartons are thrust inwardly and elevated by the transverse movements of a pusher plate 124 having upstanding arms 124^a and mounted at the inner end of a pusher arm 125 guided between guide plates 126—126. The 75

pusher arm is provided on its under surface with a rack 127 in mesh with a pinion 128 actuated by a rack 129 on the end of a thrust rod 130 actuated by cam mechanism 131 to advance the cartons 5 inwardly in timed series to the full line position indicated in Fig. 13, at which point they contact the inner face of a guide plate 132, provided with a series of vertical slots 133 through which the cross partition walls are thrust by mechanism 10 substantially like that shown in the Benoit Patent No. 1,970,550, and the Brown and Vaughan Patent No. 1,993,915. As the cartons are thrust inwardly along the inclined rails 114 they are elevated 15 slightly to bring the upper series of slots 49 in the carton blank into exact register with the slots 133 in the guide plate 132.

The cross wall partitions 41 are fed transversely into and through the aligned slots 49 in the body blank by the mechanism shown more particularly 20 in Figs. 11 and 13, but since this mechanism is substantially a counterpart of that shown in the Benoit Patent No. 1,970,550, a brief description only will be given of it. Since seven cross partitions are required to afford two rows of six cells 25 each in the completed carton, provision is made for seven stacks of cross partitions arranged flatwise in column form and supported within T-shaped standards 134 (Fig. 11), which provide seven open chutes or hoppers for the columns of 30 cross partitions. With each operation of the machine, seven cross partitions are fed inwardly from the bottoms of the respective stacks by means of a feed plate 135 provided with a notch or shoulder 136 (Fig. 12), which plate is carried 35 by a carriage 137 slideable transversely upon guide rods 138 and operated by a thrust rod 139 suitably actuated by cam mechanism 140 in properly timed relation. The carriage also carries suitable pivoted fingers 141 which are rocked or oscillated 40 to partially elevate the blanks after they have been fed forward from the stacks and are advancing toward the rear ends of a series of guideways 142 (Fig. 11), which complete the edgewise elevation of the partition blanks and guide them 45 inwardly to the slots 133 through which they are inserted into the slots in the walls of the body blank.

A step by step inward advancement of the partition blanks is effected by mechanism having a 50 four-way movement of the character fully described in the Benoit patent aforesaid, which consists briefly of a series of spaced bars 143 (Fig. 12) which partake of the in and out movements of the carriage and which are provided with depending plates 144 which in a stepped sequence 55 engage the rear edges of the partition blanks and feed them forward twice in order to project them through the slots in the body blank. Provision is made for holding the bars 143 in lowered position during the inward feeding movements so that they will engage the rear edges of the blanks as in Fig. 12, and for elevating the bars so that the plates 144 will clear the 60 blanks on the return movement of the bars, thus feeding them inwardly in a step by step processional movement. In view of the more complete disclosures contained in the Benoit patent aforesaid it is not deemed necessary to further describe these feeding movements which have the 65 effect of thrusting the partition blanks into the position shown in Fig. 13, at which point the upper and lower notches 43 and 42 of the cross partitions stand in alignment with the slots 49 in the body blank.

The outer projected edges of the cross partitions are held in properly aligned relation by contact with a stop bar 145 (Fig. 13) which is secured to and movable with the pusher bar 124. After the cross partitions have been thus positioned the 5 constituents of the carton are properly assembled for advancement to the next position. In order to effect this advancement it is necessary to elevate the body blank sufficiently to bring it into the bite of two sets of feed rollers 146 and 147 (Fig. 11), which stand in elevated relation with respect to the body of the carton and in position to engage the upper margins thereof, so that as the carton is advanced by the rollers 146 and 147 10 it will be suspended therefrom, with its lower or 15 folded edge riding along a guide rail 148 (Fig. 10).

In order to effect the necessary elevation of the blanks, the lifting jaw mechanism shown in 20 Figs. 12, 13 and 14 is provided. This mechanism is carried by a vertically movable slide plate 149 provided with forwardly extending ears 150 which journal a pintle 151 carrying an arm 152, which mounts a roller 153 adapted on the downward movement to ride upon the outer face of a switch 25 arm 154 pivoted upon a pin 155.

The switch arm is provided on one side with an offset shoulder 156 which furnishes the pathway for the roller 153, and at the terminus of the shoulder the roller will drop inwardly behind the 30 switch arm as indicated in dotted lines in Fig. 15, so that, upon the next upward traverse of the slide plate 149, the roller will occupy the innermost position and roll along behind the switch arm. The arrangement is one which imparts oscillatory movements to the pintle 151 which carries a finger 152^a to which is pivoted a link 153^a having its outer end pivoted to the tail 154^a of a 35 jaw member 156^a to which is secured a spring 156^b connecting at its upper end with the finger 40 152^a.

The arrangement is one which normally pulls the jaw inwardly into clamping position, but on the downward movement of the roller 153 the roller will move into contact with the tail 154^a of the jaw, which forces the jaw away from 45 clamping engagement with the carton. Thus on the downward movement of the slide plate 149 the jaw will stand in open relation to the gripping surface 157 of the slide plate, so that at this 50 stage in the operation there will be nothing to interfere with the positioning of the carton blanks by the inward movement of the pusher bar 124.

After the cross partitions have been inserted, the slide bar will be moved sufficiently to allow 55 the roller 153 to drop in behind the switch arm as indicated in dotted lines in Fig. 15, which causes the jaws to swing inwardly to the gripping position, in preparation for the lifting movement of the slide plate 149, which elevates the body of 60 the carton blank to the degree required to draw the lower ends of the slots in the body blank into engaging relation with the lower slots 42 in the cross walls. This engagement is effected by reason of the fact that the cross walls are 65 held against movement during this interval by the contact of a bar 158 (Fig. 13) which is carried by plunger rods 159, the upper ends of which are secured within lugs 160 on the slide plate in such a way as to afford the required amount of lost 70 motion to permit the slide plate to be partially elevated before any elevation of the bar 158 occurs, which bar is of sufficient weight to hold down the cross partitions during this interval and until an interlock is effected.

It will be understood from Fig. 10 that the slide plate and jaw mechanism above described are in duplicate in order to make provision for gripping the carton blanks near each end during the lifting operation. Each of the slide plates is raised and lowered by the rotation of a spur pinion 161 (Fig. 10) which engages a rack 162 on the slide plate. The pinions are mounted upon a shaft 163 carrying a pinion 164 which in turn 10 is actuated by a rack 165 at the upper end of a draw rod 166 actuated by a cam 167 in properly timed relation to elevate the carton body blanks after the cross partitions have been inserted, and the initiatory portion of the lifting movement 15 serves to interlock the cross partitions within the slots, and the final lifting movement serves to bring the upper margins of the blank into line with the rollers 146 and 147.

At this stage the assembled carton is thrust 20 forwardly by the action of a kicker bar 168 (Fig. 10) which is carried by a block 169 slidably mounted within a guideway 170 and actuated by a rocker arm 171 pivoted at 172 and having its lower end connected by a thrust rod 173 suitably 25 actuated at properly timed intervals to advance the cartons slightly until they enter the bite of the rolls 146 and with their lower edges resting upon the guide plate 148, which serves to steady the cartons and permit them to be fed forwardly 30 with the cross walls distended in transverse relation to the body. This advancement of the cartons causes them to traverse the space between two inclined guide plates 174 provided each along its lower inner edge with an angle bar 175 35 so disposed as to engage the lower edges of the outstanding partition walls, without, however, interfering with the direct forward advance of the carton body, which is advanced by the action of a series of pairs of upper rollers 176, 177, 178 40 (Fig. 16) which act in conjunction with pairs of lower feed rollers 179, 180, 181.

These upper and lower feed rollers grip the upper and lower margins of the body blanks and hold the body blanks in the direct line of advance 45 while the distended cross walls are caused to travel along the inclined angle guide bars 175 and thus be progressively elevated, with the result that at the end of this feeding movement the notches 43 in the cross walls will be elevated 50 to engage with the upper ends of the slots 49 in the body wall, thus establishing a higher point of interlock. In this condition the assembled blank enters the department E of the machine within 55 which the lower edge of the carton body is reversely folded and tucked inwardly in the manner now to be described.

The final movement of the cartons into this department of the machine is effected by a kicker bar 182 carried by a slide 183 mounted 60 upon the guide bar 184 and actuated in properly timed sequence by a lever 185 pivoted at 186 and rocked by the action of a cam 187. The upper end 188 of the lever is bifurcated to freely engage a pin 189 on the slide plate so that the 65 rocking movements of the lever will be transformed into back and forth movements of the kicker arm, which serves to give the final advancement to the cartons along the upper grooved edge 190 of a centrally disposed plunger plate 191, which at its forward end is provided with a boss 192 carrying a roller 193 which rides in a slot 194 (Fig. 26) in a guide standard 195. Up and down reciprocating movements are imparted to the grooved plunger bar by a lever arm 70 75 pivoted at its outer end 197 and actuated by

a thrust rod 198 carrying a cam head 199 operated by a cam 200 in properly timed sequence.

The plunger bar cooperates with a pair of folder bars 201 each carried by arms 202 and 203 (see Fig. 16). Each of the arms 203, at a point 5 somewhat below the middle, is provided with an inwardly extending finger 204, which fingers are hinged upon a pintle 205 (Fig. 18) carried within a sleeve 206, so that the arms are free to rock toward and from one another upon the pintle as 10 an axis. Upon the same pintle is mounted the inner end of a lever 207 pivoted at its outer end upon a fixed pivot 208, which arm is oscillated vertically and in properly timed sequence by the action of a thrust rod 210 actuated by a cam 211. 15

The lower ends of the arms 203 are projected downwardly, and each arm has pivoted thereto a toggle link 212, which links in unison are pivoted at the point 213 to the inner end of a lever arm 214 fixedly pivoted at the point 215 and actuated by a roller 216 riding upon a properly configured cam 217. The arms 202 are similar in all respects to the arms 203, except that they do not have the downward extensions below the inwardly projecting fingers 204. 25

The method of mounting and actuating the folder bars and timing and coordinating the movements imparted by the respective cams is such that as the bars are actuated they will move in the manner shown diagrammatically in Figs. 30 19 to 22 inclusive. These movements are coordinated with pressure which is imparted to the top of the carton blank by means of a grooved presser bar 218, which is moved up and down in properly timed sequence by means of a plunger rod 219 35 actuated by a cam 220. The carton blank, during the movements presently to be described, is held in position between guide plates 221 having their lower edges 222 bent inwardly in oblique relation to engage the beveled side edges of the 40 cross walls and suspend the same during the infolding movements, and the support thus afforded is supplemented by overhanging bars 223, which engage the aligned upper edges of the cross walls and hold them steadily against displacement 45 during the ensuing operations, which serve to reversely bend the folded lower edge of the carton blank and tuck it up inwardly until it assumes the final position shown in Fig. 23.

At the initial stage of these operations, the 50 carton occupies the position shown in Fig. 19 with the folder bars standing distended and with the vertically movable grooved plunger bar 191 occupying a position immediately below the folded lower edge of the carton. The first movement is imparted to the plunger bar which rises to the 55 position shown in Fig. 20, thereby flattening out the fold in the lower edge of the carton blank and distending the side walls as incidental to this operation. The side walls in being thus distended break along the grooves or score lines 33-35, 60 which gives to this portion of the carton blank the right angled configuration indicated in Fig. 20, with the angles substantially aligned with the folder bars which have notched inner edges 65 adapted to engage the ridges or angles along the score lines 35 thus presented.

As the movements progress from the position indicated in Fig. 20 to that indicated in Fig. 21, the plunger bar continues its upward thrust 70 against the center of the carton blank and along the score line 31, and also causes the bend along the score lines 33 to be drawn inwardly, which movement, together with the compressive movement imparted to the folder arms, brings the 75

bends along the score lines 35 into position to be engaged by the folder arms which are grooved or notched along their acting upper faces. With the bends along 35 thus engaged, the folder arms 5 continue to move inwardly to the position shown in Fig. 22, which causes the entire inner portion of the carton blank to collapse and infold upwardly, bending along the score lines 31, 33, 35, and approach a flatwise folded condition.

10 These movements cause the slits at 51 to spread sufficiently to engage the sides of the cross walls and thus permit the infolding of the carton into the substantially flatwise condition shown in Fig. 22. During these operations the upper edge of 15 the carton body is held against vertical displacement by the contact of the grooved bar 218, which lowers from the position shown in Fig. 19 to the position shown in Figs. 20-22, to thus effectively engage and hold the carton while the infolding 20 operation is occurring. At the same time the cross walls are held against displacement by the plates 221 which, as shown in Figs. 19-21, closely embrace the outer edges of the cross walls.

This concludes the infolding operation and conditions the carton for final delivery from the machine, and at this stage the cartons are thrust forwardly into the bite of feed rollers 224 by a terminal movement imparted by the kicker arm 182, the cam 187 being so configured as to 30 part this final movement after the infolding operation has been completed. This final feeding movement by the rollers 224 carries the assembled carton blanks standing edgewise into a delivery guideway consisting of transversely extending 35 flanged rails 225-225 along which the cartons are moved by a reciprocating plunger bar 226, or in any other suitable and convenient manner.

All of the various departments of the machine are so unified and coordinated that the entire 40 operation will proceed automatically and without interruption. This is due to the fact that after the carton body blanks are first medially folded by the breaker plates in the department B of the machine, so that they stand in vertically 45 flatwise relation with their folded edge presented downwardly, the blanks progress forwardly through the machine in this upstanding position and without further stacking or reassembling, and subject only to the lateral and vertical movements required in the introduction and interlocking of the cross partitions. By thus maintaining the body blanks in folded vertically 50 standing relationship, there is no need for any interruption in the continuity of the operations, 55 since the blanks are constantly under the control of the machine.

It will of course be understood that after the infolding of the carton blanks, the final delivery of the blanks causes the cross walls, when freed 60 from confinement, to pivot upon their centers and nest flatwise against one another as they are finally stacked together at the delivery end of the machine. Although it is essential that the distended right angle relation of the cross walls 65 be maintained during the infolding operation in order to properly align the slots in the body blank and in the cross walls so that no difficulty will be experienced in effecting the movements previously described, the parts, however, during this 70 operation are adequately confined and held, so that the necessary operations will occur without interference.

In Fig. 25 we have shown a carton which is similar in all respects to the one previously 75 described, with the exception of the fact that the

two plies of the body are not connected along the medial folding line. However, the infolding mechanism of the present invention will operate on the two separate plies thus associated in substantially the same manner as in the case previously described in which a reverse bending along the medial folding line occurs. Where the two plies, however, are separately formed as in Fig. 25, it will of course be understood that no reverse bending occurs, but that the disconnected lower 10 edges constituting the base portion of the carton body will be thrust inwardly in unison, which will cause a distension of the side wall portions in the manner previously described, so that the base portion of the carton will be tucked inwardly between the side walls in the same manner as though the operation were directed upon a carton blank in which the two plies are actually connected along the folding line. It will therefore be understood that in so far as the 20 infolding mechanism is concerned, it makes no difference whether it acts upon a carton blank having a once-folded body or one in which two separate body plies stand in disconnected edge-wise relation to one another, and that it is not 25 the intention, unless otherwise indicated in the claims, to limit the invention to the employment of folding mechanism of the character pointed out in the description of the complete machine.

The machine as a whole is one which is de- 30 signed to rapidly and accurately assemble cartons of the general character described and deliver them in condition for shipment with a minimum of attention, and with proper safeguards at all stages of the operation to prevent displacement 35 of the carton blanks or jamming the machine thereby.

Although the machine as a whole has been described with particularity as to detail, it will be understood that numerous modifications in 40 structure may be introduced without departing from the spirit of the invention.

We claim:

1. In a machine for assembling cartons consisting of a slotted body and individual cross 45 walls, means for advancing the carton body with the two plies of the body standing on edge and in flatwise relation to one another and for inserting the individual cross walls through the slots in the two ply body, infolding mechanism to which the 50 assembled blank is delivered, said infolding mechanism comprising an inwardly movable member adapted to engage and impart an inward edgewise thrust to the body to cause distension of the body plies from one another, and folder means adapted to impart inward lateral pressure against the distended sides of the body in timed relation to infold the base portion 55 of the body between the side portions thereof.

2. In a machine for assembling cartons consisting of a slotted body and individual cross walls, means for advancing the carton body with the two plies of the body standing on edge and in flatwise relation to one another and for inserting the individual cross walls through the slots in the two ply body, infolding mechanism to which the 65 assembled blank is delivered, said infolding mechanism comprising an inwardly movable member adapted to engage and impart an inward edgewise thrust to the body to cause distension of the body plies from one another, folder means adapted to impart inward lateral pressure against the distended sides of the body in timed 70 relation to infold the base portion of the body between the side portions thereof, and means en- 75

gaging the opposite edges of the two ply body during the infolding operation to prevent bodily displacement thereof.

3. In a machine for assembling cartons consisting of a slotted body and individual cross walls, means for advancing the carton body with the two plies of the body standing on edge and in flatwise relation to one another and for inserting the individual cross walls through the slots in the two ply body, infolding mechanism comprising a movable member positioned to impart an inward thrust to the base of the body to cause distension of the plies, and pivotally mounted oscillating folder bars positioned to engage the sides of the body when outwardly distended by the inthrust of the movable member and to move inwardly in timed relation thereto to reverse the base portion of the body and tuck the same inwardly between the side portions thereof.
4. In a machine for assembling cartons consisting of a slotted body and individual cross walls, means for advancing the carton body with the two plies of the body standing on edge and in flatwise relation to one another and for inserting the individual cross walls through the slots in the two ply body, infolding mechanism comprising a movable member positioned to impart an inward thrust to the base of the body to cause distension of the plies, pivotally mounted oscillating folder bars positioned to engage the sides of the body when outwardly distended by the inthrust of the movable member and to move inwardly in timed relation thereto to reverse the base portion of the body and tuck the same inwardly between the side portions thereof.

5. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank, infolding mechanism to which the assembled blank is delivered by the advancing means, said infolding mechanism comprising a vertically movable member adapted to impart an inward thrust to the folded edge of the body blank, and folder bars adapted concurrently to impart inward lateral pressure against the sides of the body blank in timed relation to reverse the fold in the blank and tuck the base portion of the body blank inwardly between the side portions thereof.

6. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank and for holding the cross walls in distended relation during such advancement, infolding mechanism to which the assembled blank is delivered by the advancing means, said infolding mechanism comprising a vertically movable member adapted to impart an inward thrust to the folded edge of the body blank, and folder bars adapted con-

currently to impart inward lateral pressure against the sides of the body blank in timed relation to reverse the fold in the blank and tuck the base portion of the body blank inwardly between the side portions thereof.

7. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank and for holding the cross walls in distended relation and elevating them relatively to the body blank to interlock therewith during the period of advancement, infolding mechanism to which the assembled blank is delivered by the advancing means, said infolding mechanism comprising a vertically movable member adapted to impart an inward thrust to the folded edge of the body blank, and folder bars adapted concurrently to impart inward lateral pressure against the sides of the body blank in timed relation to reverse the fold in the blank and tuck the base portion of the body blank inwardly between the side portions thereof.

8. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank, infolding mechanism to which the assembled blank is delivered by the advancing means, said infolding mechanism comprising a vertically movable member adapted to impart an inward thrust to the folded edge of the body blank, and folder bars adapted concurrently to impart inward lateral pressure against the sides of the body blank in timed relation to reverse the fold in the blank and tuck the base portion of the body blank inwardly between the side portions thereof, and means engaging the top edge of the body blank during the infolding operation to prevent bodily displacement thereof.

9. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank and for holding the cross walls in distended relation during such advancement, infolding mechanism to which the assembled blank is delivered by the advancing means, said infolding mechanism comprising a vertically movable member adapted to impart an inward thrust to the folded edge of the body blank, folder bars adapted concurrently to impart inward lateral pressure against the sides of the body blank in timed relation to reverse the fold in the blank and tuck the base portion of the body blank inwardly between the side portions thereof, and means engaging the top edge of

the body blank during the infolding operation to prevent bodily displacement thereof.

10. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank and for holding the cross walls in distended relation and elevating them relatively to the body blank to interlock therewith during the period of advancement, infolding mechanism to which the assembled blank is delivered by the advancing means, said infolding mechanism comprising a vertically movable member adapted to impart an inward thrust to the folded edge of the body blank, folder bars adapted concurrently to impart inward lateral pressure against the sides of the body blank in timed relation to reverse the fold in the blank and tuck the base portion of the body blank inwardly between the side portions thereof, and means engaging the top edge of the body blank during the infolding operation to prevent bodily displacement thereof.

11. In a machine for assembling cartons consisting of a slotted body wall and individual cross walls, means for once-folding the body wall and means for inserting the individual cross walls, means for advancing the carton thus assembled while standing with its folded edge presented outwardly, infolding mechanism to which the assembled blank is delivered by the advancing means, said infolding mechanism comprising an inwardly movable member adapted to engage and impart an inward thrust to the folded edge of the body blank, and folder bars adapted to impart inward lateral pressure against the sides of the body blank in timed relation to reverse the fold in the body blank and tuck the base portion of the body blank inwardly between the side portions thereof.

12. In a machine for assembling cartons consisting of a slotted body wall and individual cross walls, means for once-folding the body wall and means for inserting the individual cross walls, means for advancing the carton thus assembled while standing with its folded edge presented outwardly, infolding mechanism to which the assembled blank is delivered by the advancing means, said infolding mechanism comprising an inwardly movable member adapted to engage and impart an inward thrust to the folded edge of the body blank, folder bars adapted to impart inward lateral pressure against the sides of the body blank in timed relation to reverse the fold in the body blank and tuck the base portion of the body blank inwardly between the side portions thereof, and means engaging the opposite edge of the body blank during the infolding operation to prevent bodily displacement thereof.

13. In a machine for assembling cartons consisting of a slotted body wall and individual cross walls, means for once-folding the body wall and means for inserting the individual cross walls, means for advancing the carton thus assembled while standing with its folded edge presented outwardly, infolding mechanism to which the assembled blank is delivered by the advancing means, said infolding mechanism comprising a movable member positioned to impart an inward thrust to the folded edge of the body blank, and pivotally

mounted oscillating folder bars positioned to engage the sides of the body blank when outwardly distended by the thrust of the movable member and to move inwardly in timed relation thereto to reverse the fold in the blank and tuck the base portion of the body blank inwardly between the side portions thereof.

14. In a machine for assembling cartons consisting of a slotted body wall and individual cross walls, means for once-folding the body wall and means for inserting the individual cross walls, means for advancing the carton thus assembled while standing with its folded edge presented outwardly, infolding mechanism to which the assembled blank is delivered by the advancing means, said infolding mechanism comprising a movable member positioned to impart an inward thrust to the folded edge of the body blank, pivotally mounted oscillating folder bars positioned to engage the sides of the body blank when outwardly distended by the thrust of the movable member and to move inwardly in timed relation thereto to reverse the fold in the blank and tuck the base portion of the body blank inwardly between the side portions thereof, and means engaging the opposite edge of the body blank during the infolding operation to prevent bodily displacement thereof.

15. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank, infolding mechanism to which the assembled blank is delivered by the advancing means, said infolding mechanism comprising a vertically movable member adapted to impart an inward thrust to the folded edge of the body blank, and folder bars adapted to impart inward lateral pressure against the sides of the body blank in timed relation to reverse the fold in the blank and tuck the base portion of the body blank inwardly between the side portions thereof, and means for holding the distended cross walls against displacement during the infolding operation.

16. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank and for holding the cross walls in distended relation during such advancement, infolding mechanism to which the assembled blank is delivered by the advancing means, said infolding mechanism comprising a vertically movable member adapted to impart an inward thrust to the folded edge of the body blank, and folder bars adapted to impart inward lateral pressure against the sides of the body blank in timed relation to reverse the fold in the blank and tuck the base portion of the body blank inwardly between the side portions thereof, and means for holding the distended cross walls against displacement during the infolding operation.

17. In a machine for assembling cartons con-

- 5 sisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank and for holding the cross walls in distended relation and elevating them relatively to the body blank to interlock therewith during the period of advancement, infolding mechanism to which the assembled blank is delivered by the advancing means, said infolding mechanism comprising a vertically movable member adapted to impart an inward thrust to the folded edge of the body blank, and folder means adapted concurrently to impart inward lateral pressure against the sides of the body blank in timed relation to reverse the fold in the blank and tuck the base portion of the body blank inwardly between the side portions thereof, and means for holding the distended cross walls against displacement during the infolding operation.
- 10 18. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank, infolding mechanism to which the assembled blank is delivered by the advancing means, said infolding mechanism comprising a vertically movable member adapted to impart an inward thrust to the folded edge of the body blank, and folder bars adapted to impart inward lateral pressure against the sides of the body blank in timed relation to reverse the fold in the blank and tuck the base portion of the body blank inwardly between the side portions thereof, and means for holding the distended cross walls against displacement during the infolding operation.
- 15 19. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank, infolding mechanism to which the assembled blank is delivered by the advancing means, said infolding mechanism comprising a vertically movable member adapted to impart an inward thrust to the folded edge of the body blank, and folder bars adapted to impart inward lateral pressure against the sides of the body blank in timed relation to reverse the fold in the blank and tuck the base portion of the body blank inwardly between the side portions thereof, and means for engaging the top edge of the body blank during the infolding operation to prevent bodily displacement thereof, and means for holding the distended cross walls against displacement during the infolding operation.
- 20 20. In a machine for assembling cartons consisting of a slotted body wall and individual cross walls, the combination of means for folding the body wall along an intermediate folding line to provide a once-folded body blank, means for advancing said body blank while standing upright upon its folded edge, means for inserting the cross walls through the slots in the once-folded body blank while standing edgewise, means for advancing the assembled blank and for holding the cross walls in distended relation and elevating them relatively to the body blank to interlock therewith during the period of advancement, infolding mechanism to which the assembled blank is delivered by the advancing means, said infolding mechanism comprising a vertically movable member adapted to impart an inward thrust to the folded edge of the body blank, folder bars adapted to impart inward lateral pressure against the sides of the body blank in timed relation to reverse the fold in the blank and tuck the base portion of the body blank inwardly between the side portions thereof, means engaging the top edge of the body blank during the infolding operation to prevent bodily displacement thereof, and means for holding the distended cross walls against displacement during the infolding operation.
- 25 21. In a machine for assembling cartons consisting of a slotted body wall and individual cross walls, the combination of means for once-folding the body blank along an intermediate folding line, means for inserting the cross walls through slots in the once-folded body blank, means for advancing the carton blank thus assembled, infolding means to which the carton blanks are advanced, said means comprising a centrally disposed plunger plate adapted to engage the folded lower edge of the body blank, means for imparting an upward thrust to the plunger plate to reverse the fold and infold the base portion of the body blank, a pair of oppositely disposed oscillating folder bars positioned to engage the side walls of the body blank and in unison to impart an inward thrust to the side walls in timed relation to the infolding movement imparted by the plunger plate, and cams for actuating the folder bars and plate in timed relation to one another.
- 30 22. In a machine for assembling cartons consisting of a slotted body wall and individual cross walls, the combination of means for once-folding the body blank along an intermediate folding line, means for inserting the cross walls through slots in the once-folded body blank, means for advancing the carton blank thus assembled, infolding means to which the carton blanks are advanced, said means comprising a centrally disposed plunger plate adapted to engage the folded lower edge of the body blank, means for imparting an upward thrust to the plunger plate to reverse the fold and infold the base portion of the body blank, a pair of oppositely disposed oscillating folder bars positioned to engage the side walls of the body blank and in unison to impart an inward thrust to the side walls in timed relation to the infolding movement imparted by the plunger plate, cams for actuating the folder bars and plate in timed relation to one another, and a movable presser bar adapted when lowered to engage the upper edge of the body blank to hold the same against displacement during the infolding pressure applied to the base portion of the body blank.
- 35 23. In a machine for assembling cartons con-

sisting of a slotted body wall and individual cross walls, the combination of means for once-folding the body blank along an intermediate folding line, means for inserting the cross walls 5 through slots in the once-folded body blank, means for advancing the carton blank thus assembled, infolding means to which the carton blanks are advanced, said means comprising a centrally disposed plunger plate adapted to engage the folded lower edge of the body blank, means for imparting an upward thrust to the plunger plate to reverse the fold and infold the base portion of the body blank, a pair of oppositely disposed oscillating folder bars positioned 10 to engage the side walls of the body blank and in unison to impart an inward thrust to the side walls in timed relation to the infolding movement imparted by the plunger plate, cams for actuating the folder bars and plate in timed relation to one another, and oppositely disposed guide plates for 15 engaging the opposite edges of the distended cross walls for holding the same in distended relation during the infolding operation.

24. In a machine for assembling cartons consisting of a slotted body wall and individual cross walls, the combination of means for once-folding the body blank along an intermediate folding line, means for inserting the cross walls through slots 20 in the once-folded body blank, means for advancing the carton blank thus assembled, infolding means to which the carton blanks are advanced, said means comprising a centrally disposed plunger plate adapted to engage the folded lower edge of the body blank, means for imparting an upward thrust to the plunger plate to reverse the fold and infold the base portion of the body blank, a pair of oppositely disposed oscillating folder bars positioned to engage the side walls of the body blank and in unison to impart an inward 25 thrust to the side walls in timed relation to the infolding movement imparted by the plunger plate, cams for actuating the folder bars and plate in timed relation to one another, a movable presser bar adapted when lowered to engage the upper edge of the body blank to hold the same against displacement due to the infolding pressure applied 30 to the base portion of the body blank, and oppositely disposed guide plates for engaging the opposite edges of the distended cross walls for holding the same in distended relation during the infolding operation.

25. In a machine for assembling cartons consisting of a slotted body wall and individual cross walls, the combination of means for once-folding the body blank along an intermediate folding line, means for inserting the cross walls through slots 35 in the once-folded body blank, means for advancing the carton blank thus assembled, infolding means to which the carton blanks are advanced, said means comprising a centrally disposed plunger plate adapted to engage the folded lower edge of the body blank, means for imparting an upward thrust to the plunger plate to reverse the fold and infold the base portion of the body blank, a pair of folder bars adapted each to engage the side wall of the carton along a folding line, arms for supporting the folder bars, each of said arms having an inwardly extending finger and means for pivoting said fingers at a point 40 intermediate the arms, a lever pivoted to said pivotal means for imparting vertical movements thereto, lever means for oscillating the lower ends of the arms toward and from one another upon the pivotal means as a center, and cam devices for actuating the lever and the oscillating means in timed relation to the movements of the plunger plate to move the folder bars inwardly to compress the side walls of the body blank in timed relation to the infolding movement imparted by the plunger plate, and oppositely disposed guide plates for engaging the opposite edges of the distended cross walls for holding the same in distended relation during the infolding operation.

means in timed relation with the movements of the plunger plate to move the folder bars inwardly to compress the side walls of the body blank in timed relation to the infolding movements imparted by the plunger plate.

26. In a machine for assembling cartons consisting of a slotted body wall and individual cross walls, the combination of means for once-folding the body blank along an intermediate folding line, means for inserting the cross walls through slots 10 in the once-folded body blank, means for advancing the carton blank thus assembled, infolding means to which the carton blanks are advanced, said means comprising a centrally disposed plunger plate adapted to engage the folded lower edge of the body blank, means for imparting an upward thrust to the plunger plate to reverse the fold and infold the base portion of the body blank, a pair of folder bars adapted each to engage the side wall of the carton along a folding line, arms for supporting the folder bars, each of said arms having an inwardly extending finger and means for pivoting said fingers at a point intermediate the arms, a lever pivoted to said pivotal means for imparting vertical movements 15 thereto, lever means for oscillating the lower ends of the arms toward and from one another upon the pivotal means as a center, and cam devices for actuating the lever and the oscillating means in timed relation to the movements of the plunger plate to move the folder bars inwardly to compress the side walls of the body blank in timed relation to the infolding movements imparted by the plunger plate, and a movable presser bar adapted when lowered to engage the upper edge 20 of the body blank to hold the same against displacement due to the infolding pressure applied to the base portion of the body blank.

27. In a machine for assembling cartons consisting of a slotted body wall and individual cross walls, the combination of means for once-folding the body blank along an intermediate folding line, means for inserting the cross walls through slots 25 in the once-folded body blank, means for advancing the carton blank thus assembled, infolding means to which the carton blanks are advanced, said means comprising a centrally disposed plunger plate adapted to engage the folded lower edge of the body blank, means for imparting an upward thrust to the plunger plate to reverse the fold and infold the base portion of the body blank, a pair of folder bars adapted each to engage the side wall of the carton along a folding line, arms for supporting the folder bars, each of said arms having an inwardly extending finger and means 30 for pivoting said fingers at a point intermediate the arms, a lever pivoted to said pivotal means for imparting vertical movements thereto, lever means for oscillating the lower ends of the arms toward and from one another upon the pivotal means as a center, and cam devices for actuating the lever and the oscillating means in timed relation to the movements of the plunger plate to move the folder bars inwardly to compress the side walls of the body blank in timed relation to the infolding movements imparted by the plunger plate, and oppositely disposed guide plates for engaging the opposite edges of the distended cross walls for holding the same in distended relation during the infolding operation.

28. In a machine for assembling cartons consisting of a slotted body wall and individual cross walls, the combination of means for once-folding the body blank along its intermediate folding line, means for inserting the cross walls through slots 35

in the once-folded body blank, means for advancing the carton blank thus assembled, infolding means to which the carton blanks are advanced, said means comprising a centrally disposed 5 plunger plate adapted to engage the folded lower edge of the body blank, means for imparting an upward thrust to the plunger plate to reverse the fold and infold the base portion of the body blank, a pair of folder bars adapted each to engage the 10 side wall of the carton along a folding line, arms for supporting the folder bars, each of said arms having an inwardly extending finger and means for pivoting said fingers at a point intermediate the arms, a lever pivoted to said pivotal means 15 for imparting vertical movements thereto, lever means for oscillating the lower ends of the arms toward and from one another upon the pivotal means as a center, and cam devices for actuating the lever and the oscillating means in timed relation with the movements of the plunger plate to move the folder bars inwardly to compress the 20 side walls of the body blank in timed relation to the infolding movements imparted by the plunger plate, a movable presser bar adapted when lowered to engage the upper edge of the body blank to hold the same against displacement during the 25 infolding pressure applied to the base portion of the body blank, and oppositely disposed guide plates for engaging the opposite edges of the distended cross walls for holding the same in distended relation during the infolding operation.

29. In a machine for assembling cartons consisting of a slotted body wall and individual cross walls, the combination of means for once-folding 30 the body blank along an intermediate folding line and advancing the same standing edgewise upon said fold, cross wall inserting means adapted to receive the blank and comprising a reciprocating plunger bar for moving the once-folded blank laterally in edgewise standing relation, a slotted 35 plate against which the carton is moved by the plunger bar, means for introducing the cross walls through the slotted plate and through the slots in the body blank, jaw mechanism for elevating the body blank, and means for holding the inserted cross walls against elevation to effect interlocking engagement between the cross walls and the body wall, means for advancing the assembled carton with the body wall thus elevated, and infolding 40 means for reversing the first mentioned intermediate fold in the body blank and tucking the base portion of the body blank upwardly on opposite sides of said reversed fold and between the side walls thereof.

30. In a machine for assembling cartons consisting of a slotted body wall and individual cross walls, the combination of means for once-folding the body blank along an intermediate folding line and advancing the same standing edgewise upon 45 said fold, cross wall inserting means adapted to receive the blank and comprising a reciprocating plunger bar and inclined transverse rails engaging the folded base of the body blank for moving the once-folded blank laterally in edgewise standing relation, a slotted plate against which the 50

carton is moved by the plunger bar, means for introducing the cross walls through the slotted plate and through the slots in the body blank, jaw mechanism for elevating the body blank, and means for holding the inserted cross walls against elevation to effect interlocking engagement between the cross walls and the body wall thus elevated, and infolding means for reversing the first mentioned intermediate fold in the body blank and tucking the base portion of the body blank 5 upwardly on opposite sides of said reversed fold and between the side walls thereof.

31. In a machine for assembling cartons consisting of a slotted body wall and individual cross walls, the combination of means for feeding forward a procession of scored body blanks lying in flatwise unfolded condition, breaker means for folding and breaking the blank along the score lines, said means comprising a suspended anvil member having on oppositely facing sides an angular formation conformable to the breaking points along the score lines of the blank, a pair of oppositely disposed oscillating folder plates having an angular configuration complementary to the angled surfaces of the anvil and pivoted to oscillate toward and from the opposite sides of the anvil and adapted when distended to permit flatwise insertion of the blank beneath the free edge of the anvil plate and when oscillated toward the sides of the anvil 20 plate to fold the blank along an intermediate score line contacting the free edge of the anvil plate and to carry the side portions of the blank into contact with the angled side faces of the anvil to break the blank along the score lines, 25 and mechanism and connections for oscillating the folder plates.

32. In a machine for assembling cartons consisting of a slotted body wall and individual cross walls, the combination of means for feeding forward a procession of scored body blanks lying in flatwise unfolded condition, breaker means for folding and breaking the blank along the score lines, said means comprising an anvil member having on each of its sides an angular 30 formation conformable to the breaking points along the score lines of the blank, a pair of oscillating folder plates having an angular configuration complementary to the angled surfaces of the anvil and pivoted to oscillate toward and from the anvil and adapted when distended to permit flatwise insertion of the blank and when oscillated toward the anvil plate to fold the blank along an intermediate score line and to carry the side portions of the blank into contact with the angled side faces of the anvil to break the blank along the score lines, and cam mechanism and connections for oscillating the folder plates, the anvil being provided with a slot, and kicker means adapted to be moved 35 inwardly within said slot to partially eject the blank after folding.
